UNITED STATES PATENT OFFICE.

HILAND L. BURDICK, OF GREENFIELD, MASSACHUSETTS.

MICROMETER.

1,174,052.

Specification of Letters Patent.

Patented Mar. 7, 1916.

Application filed June 24, 1914. Serial No. 847,061.

To all whom it may concern:

Be it known that I, HILAND L. BURDICK, citizen of the United States, residing at Greenfield, in the county of Franklin and 5 State of Massachusetts, have invented certain new and useful Improvements in Micrometers, of which the following is a specification.

This invention relates to an improvement 10 in micrometers or gages for taking the measurements of threads of screw-threaded articles.

The object of my invention is to provide an improved head or anvil for a micrometer 15 whereby the diameter of threads of different pitch may be measured by the same instrument, instead of, as heretofore required, a separate instrument for each size of pitch.

The invention relates to still other novel 20 features of construction and combinations of parts which will be hereinafter more fully described and pointed out in the claims.

In the accompanying drawings: Figure 1 is a view in elevation greatly enlarged; Fig. 25 2 is an enlarged vertical sectional view; Fig. 3 is an enlarged plan view of the anvil, and Fig. 4 is a view showing the improved anvil attached to a micrometer.

A represents the anvil holder, which is 30 adapted to be supported in the frame B of the micrometer C. The anvil holder A is preferably provided with a bifurcated or forked end 2. Mounted between the forked end 2 of the anvil holder is a cylindrical anvil 3, which is held between the forked end by a screw 4. Upon the peripheral face of the anvil 3 is a plurality of sets of teeth 5, 5, 35 each set consisting of two teeth, the teeth of each set being of a different size, that is, no two sets of teeth are alike, as the teeth of the various sets are of different thicknesses, and the furrows between the teeth are of different depths so that by placing the thread between the two teeth of a set and the point of 40 the micrometer C the pitch diameter of a threaded article can be obtained.

The instrument herein disclosed is intended 45 for measuring from 7 pitch to 40 pitch, but may be made to measure a thread of any 50 degree or pitch.

When it is desired to turn the anvil for

bringing the proper set of teeth into the desired position for measuring as to the pitch diameter of a given thread, the set of teeth will be brought so that they are located at 55 the apex of the forked end, whereupon the screw 4 will be turned for contracting the forked ends to hold the tool against movement.

From the foregoing it will be seen that I 60 have provided a very simple apparatus for obtaining the pitch diameter of threaded articles, and which can be constructed for obtaining measurements of any pitch, and hence I do not wish to limit myself to the 65 exact construction and arrangement herein set forth, but:

I claim:

1. An attachment for micrometers comprising an anvil holder having a rotatable 70 member connected thereto, provided with a plurality of sets of teeth on the periphery thereof, each set consisting of two teeth, said teeth being adapted to receive therebetween the thread of a threaded article to be measured 75 for the purpose of obtaining the diameter at the base of the thread of said article.

2. An attachment for micrometers comprising an anvil holder having a rotatable anvil connected thereto, provided with a 80 plurality of sets of teeth on the periphery thereof, each set consisting of two teeth, means on said anvil holder for holding said anvil where set, whereby the teeth on the anvil may be placed against the thread of a 85 threaded article to be measured and so measure the diameter at the base of the threads of said article.

3. An attachment for a micrometer comprising an anvil holder having a forked end, 90 a rotatable member mounted therein provided with a plurality of sets of teeth on the periphery thereof, each set consisting of two teeth, said teeth being adapted to receive therebetween the thread of a threaded article 95 to be measured for the purpose of obtaining the diameter at the base of the thread of said article, and means for rotatably supporting the member on the anvil holder and for holding the set of teeth against rotation 100 when brought into position for use.

4. An attachment for a micrometer con-

sisting of an anvil holder, an anvil rotatably mounted thereon, sets of teeth on said anvil so arranged that upon the rotation of said anvil the sets of teeth will successively be in a position to engage the threads of a threaded article of which the diameter at the base of the threads is to be ascertained.

In testimony whereof I affix my signature, in the presence of two witnesses.

HILAND L. BURDICK.
